UNITED STATES PATENT OFFICE.

GEORGE H. HOLLAND, OF ST. LOUIS, MISSOURI, ASSIGNOR TO THE BRIDGE & BEACH MANUFACTURING COMPANY, OF MISSOURI.

DESIGN FOR A HEATING-STOVE.

SPECIFICATION forming part of Design No. 22,542, dated June 13, 1893.

Application filed April 4, 1893. Serial No. 469,048. Term of patent 7 years.

To all whom it may concern:

Be it known that I, GEORGE H. HOLLAND, a citizen of the United States, residing at St. Louis, State of Missouri, have invented 5 and produced a new and original Design for Stoves, of which the following is a full, clear, and exact description, reference being had to the accompanying drawing, wherein the figure represents a perspective view of a stove 10 ornamented with my new design.

The design relates particularly to an upright cylindrically shaped stove, the base of which is in the form of a square having rounded corners, this base being mounted on a sub- 15 base from the corners of which the legs project downwardly and outwardly. The sub-base and legs are ornamented with scrolls, whose ends are split to form leaves. The base proper is formed tapering, its sides be- 20 ing ornamented by the representation of leaves, and in the front, is a door formed with the usual draft openings, between and on each side of which are scrolls. Around the outer edge of the door is arranged a line 25 of scrolls, as shown.

Projecting laterally from the upper portion of the base, are foot rests, ornamented on their supports and upper faces by scrolls and flutes, these latter extending along the length 30 of the supports.

The lower portion of the body is tapered downwardly, being ornamented by vertical ribs, the lower ends of some of which being connected so as to form loops. Above this 35 tapered portion of the body is arranged a downwardly extending flange projecting beyond and over the tapered lower portion of the cylindrical body. The body portion of

the stove above this flange has vertical and parallel sides and is provided with two doors 40 each having draft openings, which are surrounded by scrolls, the lower being further ornamented by having a panel above the draft openings, in which panel a name-plate is arranged. 45

On each side face of the doors in vertical panels are arranged series of scrolls which terminate in a spray of leaves at their ends.

Immediately above, and extending beyond the sides of the cylindrical body portion is 50 the base flange of the top in the form of a quadrant of a circle, having around its upper face a series of scrolls. Above those scrolls is a bead, which separates the same from a number of leaves extending around the top, 55 which leaves have their usual stems and tendrils.

The swinging top is ornamented at its bottom with vertical side walls, from which extend upwardly and inwardly the split scrolls 60 forming a crown. On the top of this crown, is an urn, formed with the rounded ends and cylindrical body portion, which is ornamented by the representation of a number of full blown flowers. At the sides of the urn are 65 dragons, forming the handles.

What I claim is—

The herein described design for stoves, substantially as shown.

In testimony whereof I hereunto affix my 70 signature, in presence of two witnesses, this 31st day of March, 1893.

GEO. H. HOLLAND.
